Attorneys

UNITED STATES PATENT OFFICE.

CARL U. SENTER, OF LOS ANGELES, CALIFORNIA.

PORTABLE WALL BRACKET.

Application filed May 19, 1926. Serial No. 110,138.

My invention is a portable wall bracket for an electric light, adapted to be suspended from a picture molding and to be shiftable therealong.

5 An object of my invention is to provide a portable wall bracket for an adjustable electric lamp, whereby the bracket may be suspended from a picture molding and shifted therealong, the device being adjustable 10 to position the electric lamp at different elevations and to allow inclining of the lamp or swivelling same horizontally or in any other desired position.

Another object of my invention is a portable wall bracket adapted to be suspended from a picture molding in which the electric light wire passes downwardly through hollow telescopic tubes to a flexibly jointed conduit leading to an electric light, the telescopic sections being provided with cleats 20 for winding the excess electric wire or cord thereon.

In constructing my invention of a portable wall bracket I utilize a hook with horizontally extending ends, the hook being adapted to engage over a picture molding and the horizontal ends being adapted to fit in the groove of the molding against the wall. A tube depends from the hook having 25 an inner telescopic tube slidable therein and adjustable in different elevations. By means of a jointed conduit the electric lamp may be positioned at different inclinations and swivelled horizontally or in any other desired position. The electric wire passes downwardly through the telescopic tubes and such tubes are provided with adjustable cleats for coiling the wire when the bracket is removed from the wall.

40 My invention will be more readily understood from the following description and drawings, in which:

Figure 1 is a side elevation of my portable wall bracket in position on the wall;

45 Fig. 2 is a front elevation enlarged of a wall bracket;

Fig. 3 is a vertical section on the line 3—3 of Fig. 2;

50 Fig. 4 is a broken front elevation showing the hook with the lateral extensions for engaging the picture molding to prevent rocking.

55 My bracket comprises a hook 1 which has lateral extensions 2, the hook being adapted to engage over picture molding 3 which

may be secured on a wall 4. The hook is of substantial construction sufficient to carry the weight and have a pleasing appearance. A nail hole 5 extends through the shank portion 6 of the hook and an outer tube 7 extends downwardly from the shank of the hook. An inner telescopic tube 8 is slidable vertically in the outer tube, the outer tube preferably having a split end 9 with a clamping collar 10, whereby the inner tube 65 may be located at any position.

A jointed conduit designated generally by the numeral 11 comprises an inner section 12 having a hinged connection 13 to the inner tube 8. This hinged connection has a 70 clamp screw 14 or the like to clamp the conduit in adjusted position. The axis of the pivot 13 is horizontal. A middle section 14 is connected to the section 12 by a vertical pivot 15 having a clamp screw 16. The outer 75 section 17 is connected to the middle section 14 by a universal joint 18, this joint being of a tight fitting type having friction resistance, whereby the lamp socket 19 and the reflector 20 may be held in any position in 80 relation to the universal joint; the lamp bulb 21 being positioned in the socket and centered relative to the reflector 20.

The lamp wire or cord 22 preferably has an ordinary socket 23 on one end and enters 85 the tube 7 through an aperture 24 passing downwardly therethrough and around the joint 13 by means of apertures 25 and 26 in the tubes 8 and the inner section 12 of the conduit 11; thus forming a slight loop 27. 90 The cord has a second loop around the joint 15, preferably passing through apertures 29 and 30 in the inner and middle sections 12 and 14 of the conduit 11. The wire passes through the universal joint to the socket. 95

A plurality of slidable cleats 31 have split sleeves 32 on the tube 7 and are clamped by means of clamp screws 33 whereby they may be adjusted in any suitable position. Thus for packing or storage the inner tube 8 may be telescoped at full distance in the tube 7 and the surplus electric cord or wire wound or coiled on the cleats 31. These cleats may also be utilized for any surplus wire which leads from an electric light socket. 100 105

By means of the jointed conduit 11 the lamp may be positioned in different positions as indicated by the full and dotted lines of Figs. 1 and 2 and the whole conduit may be raised and lowered by telescopic 110

ing the tubes 7 and 8. The extensions 2 of the hook not only secure the hook in firm relation to the picture molding but prevent rocking or swinging of the device on the molding.

Although my invention is of a simple character and is designated as designed particularly for picture moldings, the nail hole allows same to be secured on a wall or other structure when a picture molding is not installed in a room.

It will be apparent that the general construction and specific details of my invention may be considerably changed to adapt same to different constructions and for different arrangements of ornamentation, etc. Such changes however, would be within the spirit of my invention as set forth in the description, drawings and claim.

Having described my invention, what I claim is:

A portable wall bracket comprising in combination a hook having lateral extensions adapted to engage behind a picture molding, an outer tube rigidly connected to the hook and depending therefrom, an inner tube telescoping in the outer tube, means to secure said tubes in desired relative position, a lamp supporting device at the lower end of the inner tube, an electric light wire passing through the said tubes, there being in addition cleats secured to the outer tube, one of said cleats being adjustable and adapted to allow coiling of the electric light wire thereon.

In testimony whereof I have signed my name to this specification.

CARL U. SENTER.
